CLAIM

The ornamental design for surfaces of a container, as shown and described.

DESCRIPTION

FIG. 1 is a front perspective view of surfaces of a container showing my new design;

FIG. 2 is a side elevation view thereof;

FIG. 3 is a front elevation view thereof;

FIG. 4 is a top plan view thereof;

FIG. 5 is a rear elevation view thereof;

FIG. 6 is a side elevation view thereof;

FIG. 7 is a bottom plan view thereof;

FIG. 8 is a plan view of an unfolded blank condition therefor;

FIG. 9 a top plan view thereof;

FIG. 10 is a side elevation view thereof;

FIG. 11 is another side elevation view thereof;

FIG. 12 is bottom plan view thereof; and,

FIG. 13 is a plan view thereof opposite that shown in FIG. 8. The broken line portion of the figure drawings is included to show unclaimed subject matter only and forms no part of the claimed design.
